G. W. WILSON

FENCE STRUCTURE

Filed May 13, 1922

Inventor

G. W. Wilson

By Watson E. Coleman
Attorney

UNITED STATES PATENT OFFICE.

GEORGE W. WILSON, OF HOPKINSVILLE, KENTUCKY.

FENCE STRUCTURE.

Application filed May 13, 1922. Serial No. 560,584.

To all whom it may concern:

Be it known that GEORGE W. WILSON, a citizen of the United States, residing at Hopkinsville, in the county of Christian and State of Kentucky, has invented certain new and useful Improvements in Fence Structures, of which the following is a specification, reference being had to the accompanying drawings.

10 This invention relates to certain improvements in fence structures and it is primarily an object of the invention to provide a novel and improved device of this general character which is of a portable type and which 15 may be assembled in working position without the necessity of posts or kindred supporting means.

The invention consists in the details of construction and in the combination and arrangement of the several parts of my improved fence structure whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a fragmentary view in top plan illustrating a portable fence constructed in accordance with an embodiment of my invention;

Figure 2 is a fragmentary view in elevation illustrating adjacent sections comprised in my improved fence structure;

40 Figure 3 is a view in perspective of one of the connecting or coupling members comprised in my improved fence;

Figure 4 is a view in perspective of one of the plates comprised in the device illustrated in Figure 3; and

Figure 5 is a view in perspective of the second plate comprised in the device as illustrated in Figure 2.

As disclosed in the accompanying drawings, my improved fence structure comprises a plurality of separable sections S of desired dimensions but in practice I find it best to have each of said sections substantially one rod in length.

55 Each of the sections S, as herein dis-

closed, comprises a metallic frame 1 with which is associated a wire fabric 2.

In assembling the fence the adjacent sections S are disposed in angular relation whereby the structure is effectively maintained in working position without the necessity of posts or kindred supports and in a manner whereby the fence structure is readily portable. Adjacent sections are 60 detachably connected by the coupling members or clamps C, said coupling members or clamps C permitting the adjacent sections to have relative swinging movement in order that said adjacent sections may be arranged in the preferred angular relation and at the 65 same time the coupling members or clamps C hold the adjacent sections against separation.

Each of the coupling members or clamps C comprises two elongated plates 3 and 4, 70 the central portion of the plate 3 having an elongated slot 5 of such length to permit the insertion therethrough of the second section 4 when the side faces of the sections 4 are disposed substantially in parallelism 75 with the longitudinal edges of the opening 5.

The central portion of the plate 4 is provided in its opposite longitudinal margins with notches or recesses 6 which, when said plate 4 is given a one-fourth turn after being inserted through the opening 5, receives the portions of the plate 3 defining the longitudinal margins of the opening 5. By this 80 means the plates 3 and 4 are effectively held in assembled relation but in a manner whereby said plates 3 and 4 may be readily separated as the occasions of practice require.

The notches or recesses 6 are elongated so that the plates 3 and 4 may have relative swinging movement to permit the end portions of said assembled plates 3 and 4 to receive therebetween the adjacent end members 7 in sections S. In order that the adjacent ends 7 of the sections S may be effectively engaged by the end portions of the 85 plates 3 and 4 the end portions of said plates 3 are provided with inwardly facing jaws 8 which receive therebetween and hold, when the coupling member or clamp C is in applied position, said end members 7 of the 90 sections S. An end portion of one of the members, as 3, is provided adjacent the longitudinal margin thereof with an opening 9 which aligns with an opening 10 in the adjacent end portion of the second plate 95

100 plates 3 and 4 the end portions of said plates 3 are provided with inwardly facing jaws 8 which receive therebetween and hold, when the coupling member or clamp C is in applied position, said end members 7 of the 105 sections S. An end portion of one of the members, as 3, is provided adjacent the longitudinal margin thereof with an opening 9 which aligns with an opening 10 in the adjacent end portion of the second plate 110

4 and this opening 10 is provided with an entrance slot 11 open at a longitudinal edge of the plate 4.

T denotes a tie member substantially U-shaped in form and the intermediate portion 12 of the tie member T is disposed through the opening 9. A side arm 14 of the tie member T is flattened so that when the plates 3 and 4 of a coupling member or 10 clamp C are applied the same will readily pass through the entrance slot 11 with the intermediate portion of the tie member T disposed through the opening 10. After the portion 12 of the tie member T has been 15 properly engaged within the opening 10 the tie member T is turned or swung in a direction to bring the arm 14 out of register with the entrance slot 10 and, preferably with said side arm 14 downwardly directed. 20 As the intermediate portion 12 of the tie member T is of a diameter greater than the width of the entrance slot 11 the plates 3 and 4 are effectively held against relative swinging movement and at the same time 25 maintained in locking engagement with the end members 7 of the sections S.

The coupling members or clamps C serve to effectively maintain the adjacent sections S connected and at the same time permit 30 said sections to have desired relative swinging movement.

From the foregoing description it is thought to be obvious that a fence structure constructed in accordance with my invention is particularly well adapted for use 35 by reason of the convenience and facility with which it may be assembled and operated, and it will also be obvious that my invention is susceptible of some change and 40 modification without departing from the principles and spirit thereof and for this reason I do not wish to be understood as limiting myself to the precise arrangement and formation of the several parts herein 45 shown in carrying out my invention in practice except as hereinafter claimed.

I claim:

1. A coupling member comprising two elongated plates, one of said plates having 50 an elongated slot, the second plate being insertable through said slot, said second plate having a marginal slot to receive a portion of the first plate defining the slot when said plates are in overlying relation, the 55 outer ends of the plates having opposed jaws, and means co-acting with adjacent

ends of the plates for holding the same against relative movement.

2. A coupling member comprising two elongated plates, one of said plates having an elongated slot, the second plate being insertable through said slot, said second plate having a marginal slot to receive a portion of the first plate defining the slot when said plates are in overlying relation, the outer 60 ends of the plates having opposed jaws, a tie member supported by an end portion of one of the plates and detachably engaged with the second plate when said plates are in overlying relation for holding said plates 65 against relative separating movement.

3. A coupling member comprising two elongated plates, one of said plates having an elongated slot, the second plate being insertable through said slot, said second plate 75 having a marginal slot to receive a portion of the first plate defining the slot when said plates are in overlying relation, the outer ends of the plates having opposed jaws, each 80 of said plates at adjacent end portions having openings, one of said openings having an entrance slot in communication therewith, and a substantially U-shaped tie member having its intermediate portion engageable through the openings, said intermediate portion of the tie member being of a diameter greater than the width of the entrance slot of the opening in one of the plates.

4. A coupling member comprising two 90 elongated plates, one of said plates having an elongated slot, the second plate being insertable through said slot, said second plate having a marginal slot to receive a portion 95 of the first plate defining the slot when said plates are in overlying relation, the outer ends of the plates having opposed jaws, each of said plates at adjacent end portions having openings, one of said openings having an entrance slot in communication therewith, a substantially U-shaped tie member having its intermediate portion engageable through the openings, said intermediate portion of the tie member being of a diameter greater than the width of the entrance slot 100 of the opening in one of the plates, a side arm of the tie member being insertable through said entrance slot.

In testimony whereof I hereunto affix my signature.

GEORGE W. WILSON.
